INDICATOR FOR BALL-ROLLING GAMES

Bon G. MacDougall, Chicago, Ill., assignor to
Raymond T. Moloney, Chicago, Ill.

Application June 18, 1938, Serial No. 214,525

7 Claims. (Cl. 273—121)

The invention relates to an improved ball rolling game provided for amusement purposes. More particularly the game is of that type having a back board extension serving to display and house certain releasable target indicators or objectives correlated with obstacle switches on the game table so that a ball rolling on the table and striking one of these obstacle switches will close a circuit to release a corresponding target indicator for dropping movement to indicate a "hit" for score purposes. The game is such that a shooting gallery effect is added to a pin ball type of game for the edification and amusement of the player.

15 The main object of the invention is to provide an improved ball rolling game.

Another object is to provide such a game housed in a cabinet provided with an extension for displaying and housing suitable indicator targets, 20 which are releasable and dropped from view to score "hits" when corresponding switches on the ball rolling table are closed by a ball.

Still another object is to provide a novel shooting gallery auxiliary for a ball rolling game.

25 Another object is to provide such game mechanism which is simple and foolproof in operation.

Another object is to provide a simple indicator target resetting mechanism.

30 Other important objects will be apparent to those skilled in this art as the disclosure is more fully made.

Briefly, these objects may be achieved in a pin ball type of game having a horizontal cabinet, carrying a ball rolling table sloped slightly from the horizontal and carrying in scattered relationship thereon, a plurality of spring or other bumper elements to be hit by a rolling ball. These elements constitute one side of a switch which 35 is deflected by the ball hitting same to close a respective circuit momentarily. In these circuits, so closed, are respective electromagnetic devices operative to release trips for causing indicator target elements carried in an upright display 40 housing extension of the cabinet, to be dropped from view to indicate "hits". In other words, each obstacle on the ball rolling table corresponds with and controls an indicator target to operate same. By means of the usual coin release slide 45 that releases the ball rolling game for play, means is operated to restore or re-set the dropped indicator targets to their starting, or raised display positions. So much will suffice in presenting a general understanding of the improved 50 game structure, a practicable example of which

is shown by way of illustration, in the accompanying sheets of drawings, wherein:

Figure 1 is a general plan view of the ball rolling game, the improved upright extension being shown in horizontal section, taken along the 5 line 1—1 of Figure 2;

Figure 2 is a front elevational view of the game;

Figure 3 is a side sectional view of the game taken along the line 3—3 of Figure 1, looking 10 in the direction of the arrows; and,

Figure 4 is an enlarged, side view partly in section to illustrate the details of the electromagnetic indicator target releaser mechanism.

The game comprises the usual, rectangular cabinet 10 having a front wall 11, the rear end of said cabinet having an upstanding extension 12. The cabinet carries a board or table 13 sloped slightly from the horizontal in the well known manner so that a free ball projected over the 20 table to its high end will, when losing the force that projected it, gravitate down the board to the low end thereof. Adjacent the high end of the table 13 is an upright wall, or plate 14, which carries a horizontal plate of glass 15 with the 25 walls of the cabinet 10 to cover the game table and also a vertical plate of glass to form a window 16 in the front face of the upright extension 12 to expose the interior of the latter for a purpose to appear.

30 The front wall 11 carries a hand operated ball projector of the plunger type, 17, so that when a ball is lodged thereagainst it may be projected to the high end of the table, through a side passageway 18 and around the edge of an arch 35 piece 19 in the usual manner to engage a resilient member 20 for rebound purposes. When the ball loses its momentum it then gravitates down the table to the low end thereof, adjacent the front wall 11, at which end the table 13 40 carries a raised part 21 providing sloping edges 22 to guide a ball, or balls, into a centrally positioned slot 23 formed in the part 21 and also through the table 13. Thus, balls eventually leave the board or table 13 by falling through 45 same to a position therebelow from whence in any well known manner they can be replaced one at a time to a position in the passage 18 to be acted upon by the plunger projector 17.

50 Located on the table 13 in scattered relation are suitable target or obstacle members to be impinged by a rolling ball, said members herein, for the sake of illustration, being upright coil springs 24, each having a pendant leg 25 passed normally centrally into a ferrule 26 embedded 55

in the table 13, there being such member 26 for each spring leg 25. Each spring with its leg 25 and each ferrule 26, is made of conductor material and in circuit by suitable wires 27 with a 5 source of energy, such as the battery 28 which may be carried in the cabinet 10, as shown. When a ball bumps a spring 24, the leg 25 thereof will momentarily be deflected and engage the complementary ferrule 26 and for an instant 10 close the circuit 27 for a purpose presently to appear. Each bumper spring 24 will thus serve to close a respective circuit when engaged by a ball. One ball rolling down the table may, of course, engage a number of springs 24 and thus 15 serve to close a like number of these circuits, since each bumper will be disposed in a similar circuit.

The front wall 11 also carries the usual coin released slide 29 which is used when releasing 20 the game for play as is common in this art, said slide being slidably carried in the wall 11 with its inner end engaging one leg of a bell crank lever 30 pivotedly carried on a pin 31 from the under side of the table. The bell crank has its other 25 leg pivotedly connected to a short link 32, in turn pivotedly connected to another short link 33 which is pivoted to a pin 35 on the under side of the table 13. Intermediate its ends, the link 34 has connected to it, a transverse link 36 extending under the table 13 as shown in Figure 30 1, said link 36 having a short link 37 pivoted to it, the latter by means of a pin 38 being pivotedly connected to a long lengthwise running push-pull bar 39 carried from under the table 13 by suitable guide rollers 40, as shown. The free 35 end of the bar 39 extends into the cabinet extension 12 for a purpose presently to appear.

Secured at the rear face of the cross upright plate 14 is a somewhat higher upright plate 41, the top edge of which carries a cross sill 42. 40 Opposite ends of said sill 42 carry brackets 43 and pivotedly connected thereto by pins 44 are the legs of a U-shaped bail member 45, said bail extending across the width of the extension 12, as shown. One leg of the bail 45 has rigidly fastened thereto a depending lever arm 46 which at its lower end carries a transverse extension 47 in a position to be abutted by the free end of the bar 39, as shown in Figure 3. The bail 45 of its own weight normally hangs in the position shown 50 in Figure 3 with the arm 46 engaging the corner between the plate 41 and table 13.

The side walls of the extension 12 as seen in Figure 1 carry aligned pairs of corner brackets 55 and 49 serving respectively to carry transverse vertical wall members 50 and 51, these wall members being disposed one behind the other with the same furthermore offset so that the rear wall 50 is higher. Rearward of these 60 walls, the sides of the extension 12 carry end brackets 52 between which brackets is carried a transverse channel support 53 in which is suitably carried in transverse spaced relation ten electromagnets 54, each said electromagnet being 65 in a circuit with the battery by wires such as 27, and also with a respective obstacle bumper contact switch 24 in a manner readily understandable.

Each electromagnet has a longitudinally disposed core 55 as shown in Figure 4 and the lower portion of the channel 53 adjacent each core 55 is formed with a vertical hole 56 in which is loosely pivoted an upright armature 57 pulled to a normal released position by means of a spring 58, as shown. The upper end of each armature 70

57 is formed with a U-shaped hooked end 59 passed through a slot 60 in a respective, substantially horizontally disposed lever 61, extending forwardly, and having its rear end loosely passed through and fulcrumed in a slot 62 in the 5 vertical bight portion of the channel 53.

In the present example, there are ten of these electromagnet units and ten such levers 61, five being long and five being short, so that the five long ones each extend forwardly with each provided with a front, short, upturned, bent end 63 respectively carrying an animal or like figure, such as the rabbits 64, shown. In a similar manner, the five short levers 61 each have their front ends bent up as at 65 to carry distinguishing figures such, for example, as the ducks 66 shown by way of illustration. The wall 51 serves as a backfield for the row of five rabbit figures 64 and similarly the wall 50 serves as a backfield for the five duck figures 66 shown. These figures and backfield walls are visible through the window 16 in an obvious manner. The long levers 61 extend forwardly under the wall 51 as can be seen in Figure 3. Each figure 64 and 66 serve as indicators and may, if desired, be 20 disposed on a circular disk as indicated in Figure 2 to simulate a target as is common in target shooting games. This completes the description of the details of the improved game construction.

In playing the game a ball is projected by the 30 shooter 17, through passage 18 onto the high end of the table. Eventually, as explained heretofore, the ball rolls by gravity down the table 13 to engage the bumpers and close one or more of the switches 25, 26, thereby energizing a corresponding electromagnet 54 to attract and move a corresponding armature 57 from the full line position shown in Figures 3 and 4 to the dotted line position shown, whereupon the associated lever 61 is released from the locking action of the part 59. 40 Thereupon, said lever by its weight, drops. The long levers 61 drop until their ends 63 hit the bight of the bail 45, as shown in dotted lines. In this position the figure 64 disappears from view through the window 16 and behind and below the 45 cross sill 42. In the same way the shorter levers 61 also may be dropped to drop their figures 66 from view behind the wall 51, said levers also coming to rest on the bail 45.

In resetting the game for play the slide 29 is 50 operated, the same when pushed inwardly, operating the bell crank 30 and connections described to push the bar 39 against the part 41 on lever 46. This moves the lever 46 rearwardly to the dotted line position shown in Figure 3 and consequently the bail 45 is swung upwardly to engage and move upwardly all of the fallen target carrying levers 61 to a raised position where the latches 59 will automatically be effective to lock these levers releasably in target exposing or view-ing position in an obvious manner.

The game mechanism above described achieves all of the desirable objects heretofore recited.

It is the intention to cover all changes and modifications of the example herein selected for 65 the sake of the disclosure, which do not in material respects constitute departures from the spirit and scope of the invention.

What is claimed is:

1. For a ball rolling game having a cabinet 70 carrying a table over which balls are rollable to engage and close switches associated therewith in an electrical circuit, said cabinet having a housing part formed with a window, indicators carried in the housing and arranged to correspond re- 75

spectively with the switches and mounted for movement from a display position behind the window to another position out of view, means releasably holding said indicators individually in display positions, means for carrying said indicators in a plurality of rows offset from one another, and means included in the circuit and operable when the switches are closed for respectively releasing the holding means and causing 10 corresponding indicators to be moved from display positions.

2. For a ball rolling game having a ball rolling surface and ball closed switches, an indicator means comprising an upright housing having a window, a support in the housing carrying a plurality of electromagnetic devices respectively in circuit with the switches and energizable when the switches are closed, a series of levers carried by the support with one disposed adjacent each 20 electromagnetic device, each lever carrying an indicator normally disposed in a viewing position behind the window, and an armature element for each device and comprising a latch having a portion to cooperate with and normally hold the 25 associated lever latched with the indicator in normal viewing position, said armature elements when their associated devices are energized serving to free the associated lever for movement to carry the indicator thereon from normal viewing 30 position at the window.

3. For a ball rolling game having a ball rolling surface and ball closed switches, an indicator means comprising an upright housing having a window, a support in the housing carrying a plurality of electromagnetic devices respectively in circuit with the switches and energizable when the switches are closed, a series of levers carried by the support with one disposed adjacent each 35 electromagnetic device, each lever disposed normally horizontally and having an angular bent end carrying an indicator normally disposed in a viewing position behind the window, and an armature element for each device and comprising a latch portion to cooperate with and normally hold the associated lever latched with the indicator in normal viewing position, said armature elements when their associated devices are energized serving to free the associated lever for dropping movement to carry the indicator thereon from normal viewing position at the window to a non-viewing position.

4. For a ball rolling game having a ball rolling surface and ball closed switches, an indicator means comprising an upright housing having a window, a support in the housing carrying a plurality of electromagnetic devices respectively in circuit with the switches and energizable when the switches are closed, a series of levers carried by the support with one disposed adjacent each 50 electromagnetic device, each lever carrying an indicator normally disposed in a viewing position behind the window, an armature element for each device and comprising a latch having a portion to cooperate with and normally hold the associated lever latched with the indicator in normal viewing position, said armature elements when their associated devices are energized serving to free the associated lever for dropping movement by gravity to a non-viewing position, and means comprising a resetting means serving to limit the extent of dropping movement of the levers.

5. For a ball rolling game having a ball rolling surface and ball closed switches, an indicator means comprising an upright housing having a

window, a support in the housing carrying a plurality of electromagnetic devices respectively in circuit with the switches and energizable when the switches are closed, a series of levers carried by the support with one disposed adjacent each electromagnetic device, each lever carrying an indicator normally disposed in a viewing position behind the window, an armature element for each device and comprising a latch having a portion to cooperate with and normally hold the associated lever latched with the indicator in normal viewing position, said armature elements when their associated devices are energized serving to free the associated lever for dropping movement by gravity to a non-viewing position, and means comprising a resetting means serving to limit the extent of dropping movement of the levers, said resetting means comprising a manually movable bail hingedly carried in the housing in a manner to have its bight portion engageable by the levers when the latter are in their dropped positions.

6. For a ball rolling game having a ball rolling surface and ball closed switches, an indicator means comprising an upright housing having a window, a support in the housing carrying a plurality of electromagnetic devices respectively in circuit with the switches and energizable when the switches are closed, a series of levers carried by the support with one disposed adjacent each electromagnetic device, certain levers being shorter than the others, said levers at one end carrying indicators with the short levers carrying the indicators at a different level than the long levers, a back drop wall between the two sets of high and low indicators, said indicators normally being in a viewing position either behind the window or back drop wall, and an armature element for each device and comprising a latch having a portion normally to hold an associated lever latched with its indicator in the normal viewing position, said armature elements when their associated devices are energized serving to free the associated lever for dropping movement by gravity to carry the indicator thereon to a non-viewing position.

7. For a ball rolling game having a ball rolling surface and ball closed switches, an indicator means comprising an upright housing having a window, a support in the housing carrying a plurality of electromagnetic devices respectively in circuit with the switches and energizable when the switches are closed, a series of levers carried by the support with one disposed adjacent each electromagnetic device, certain levers being shorter than the others, said levers at one end carrying indicators with the short levers carrying the indicators at a different level than the long levers, a back drop wall between the two sets of high and low indicators, said indicators normally being in a viewing position either behind the window or back drop wall, and an armature element for each device and comprising a latch having a portion normally to hold an associated lever latched with its indicator in the normal viewing position, said armature elements when their associated devices are energized serving to free the associated lever for dropping movement by gravity to carry the indicator thereon to a non-viewing position, said long and short levers being alternately disposed to stagger the indicators when they are disposed in the normal viewing positions.

BON G. MACDOUGALL.
